UNITED STATES PATENT OFFICE.

CROZIER T. THOMPSON, OF CRIPPLECREEK, COLORADO.

FIREMAN'S HELMET.

SPECIFICATION forming part of Letters Patent No. 752,266, dated February 16, 1904.

Application filed December 6, 1902. Serial No. 134,096. (No model.)

To all whom it may concern:

Be it known that I, CROZIER T. THOMPSON, a citizen of the United States of America, residing at Cripplecreek, in the county of Teller 5 and State of Colorado, have invented certain new and useful Improvements in Helmets and Smoke-Excluders; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to a helmet and smoke-excluder for the use of firemen and others who may have occasion to enter burning buildings or other places where the smoke or noxious gases, or both, must be kept from the mouth 20 and nostrils in order to make it possible for the person to remain and perform any efficient service.

The invention is provided with receptacles 25 for chemicals, the said receptacles being in communication with the space inclosed by the device, whereby the impurities of the air resulting from breathing are neutralized or in some way changed, thus enabling the user to work for a considerable time or indefinitely 30 when cut off from a supply of pure or atmospheric air. The nature of the chemicals employed, except as above explained, will not be set forth in this specification, as nothing is claimed thereon in this application.

35 Briefly stated, my improved device consists of a garment attached to an ordinary hat or helmet, the latter being of the type worn by firemen. Instead of this specific construction of hat or helmet, however, any other suitable 40 or desirable construction for covering the head may be employed. The garment or jacket is attached to the hat or helmet so as to exclude the smoke, and it extends downwardly around the body of the wearer to the waist, or there- 45 about, where it is secured by means of a belt, tightly buckled to exclude the smoke from below. Springs are interposed in front of the belt, being located in a pocket to permit a limited degree of elasticity, while holding the

garment or jacket tightly against the body of 50 the wearer. Above the belt and inside of the garment or between the latter and the body of the wearer are located a number of receptacles adapted to hold some of the chemicals employed, sufficient space being left to allow 55 a free communication between the receptacles and the mouth and nostrils of the wearer. Another receptacle is exteriorly located and connected in front with the space inclosed by the garment by a suitable tube or conduit, its object being to permit the passage of a gas from the outer receptacle to the space within the 6c garment.

Having briefly outlined my improved device, as well as the function it is intended to 65 perform, I will proceed to describe the same in detail, reference being made to the accompanying drawings, in which is illustrated an embodiment thereof.

In the drawings, Figure 1 is an elevation 70 showing my improved device in use. Fig. 2 is a section taken through the garment. Fig. 3 is an enlarged detail view of the window located in front of the garment, through which the user is enabled to see surrounding objects. 75 Fig. 4 is an enlarged detail view illustrating the exterior receptacle applied to the garment. Fig. 5 is a perspective view of one of the interior receptacles, shown on a larger scale than in the general views. Fig. 6 is a cross-section taken through the garment where the springs are located. Fig. 7 is a detail view, partly in section, illustrating an electric illuminating device, shown on a larger scale than 80 in Figs. 1 and 2.

85 The same reference characters indicate the same parts in all the views.

Let the numeral 5 designate the hat or helmet, to the rim of which on the under side is attached the upper edge of the garment 6, as 90 shown at 7, by means of suitable fastening devices whereby a perfectly tight joint is made. This garment may be made of canvas rubber-lined or any other suitable or desirable material which is impervious to water and smoke 95 and not readily ignitable. It should also be of sufficient stiffness to stand out well from the face and head of the wearer below the rim of the

helmet, and therefore not readily collapsible. Below the rim of the helmet and directly in front of the eyes of the wearer is located a sort of window or transparent device 8, which covers an opening in the garment and is secured thereto in any suitable manner. This device is shown in detail in Fig. 3. It may be composed of isinglass or mica or other suitable transparent material. It is preferred that this material should have sufficient toughness so that it will not break easily. It must of course possess the property of transparency to a sufficient degree for the purpose. As shown in the drawings, this window is provided with wires 8^a, which protect the transparent material. The wires are attached to metal end pieces 8^b, which are attached to the garment and form a sort of sash to hold the window 8 in place.

The lower part of the garment or jacket is provided with loops 10, through which a belt 12 may be passed. To the inside of the garment in front is attached a piece of material 13, forming an inside chamber or pocket, in which are located a number of coil-springs 14, causing this portion of the garment to yield to pressure from within or without. This yielding portion of the garment is located in the zone of the belt and engages the body of the user in front where the belt buckles.

Between the belt and the window and located inside of the garment in front is a number of receptacles 15, open at the top and of the construction best shown in Fig. 5. Each of these receptacles is a box-like device having an upwardly-projecting flange 15^a, which is riveted or otherwise suitably secured to the garment in front. Projecting rearwardly from the body of the receptacle is a sort of wire or rod forming a brace 15^b, which is shaped to conform to the curvature of the body of the wearer. This brace engages the body, as shown in Fig. 2. Between the body portion of the device and the brace is an open space to permit the free circulation of air or gases within the inclosed chamber. To the upper back portion of the garment is attached a receptacle 16, from which leads a tube 17, whose extremity remote from the receptacle communicates with the interior of the garment in front, as shown at 18. This receptacle 16 is preferably made of heavy cotton web rubber-lined and air-tight, the material being of sufficient strength to withstand one hundred pounds pressure, or thereabout.

All of the joints of the device or the points of attachment of exterior parts are so formed as to exclude the smoke and surrounding gases, thus making the garment or the combined helmet and jacket perfectly air-tight.

The receptacle 16 is detachable, having straps 16^a, provided with holes to permit the entrance of buttons 6^a, attached to the garment exteriorly. This receptacle is provided

with a valved inlet 16^b at the top for the introduction of its contents. This inlet should be tightly closed after filling to prevent the escape of gas except by way of the conduit 17.

Attached exteriorly to the garment or jacket in front is an electric lamp 19, mounted on a storage battery 20, which supplies the current. This battery is attached to the garment by means of a buttoned strap 21. The lamp is surrounded by a reflecting-hood 22, open in front to permit the escape of rays of light in front of the wearer.

The arms of the garment are tight at the wrist, being composed of some suitable elastic material 6^c. (See Fig. 1.)

From the foregoing description the use and operation of my improved device will be readily understood. The jacket is slipped over the head of the wearer and drawn down until the helmet is in place on the head. The belt is then buckled around the waist sufficiently tight to exclude smoke and gases. It is assumed that before the jacket is put on the chemicals to be employed in purifying the air have been placed in the various receptacles. The head and body of the wearer as far as the waist are then enveloped and entirely protected by the air-tight jacket and helmet, enabling the user to work with impunity in places where it would otherwise be impossible for him to remain on account of smoke and gases, or both.

Having thus described my invention, what I claim is—

1. In an apparatus of the class described, the combination with a helmet, of a smoke-excluding jacket attached to the helmet and arranged to be fastened around the body of the wearer and provided with a receptacle on the inside, substantially as described.

2. The combination with a helmet, of a jacket whose upper extremity is attached to the helmet and whose lower extremity is provided with a fastening-belt, and receptacles attached to the jacket between the helmet and the belt and located on the inside of the garment for the purpose set forth.

3. The combination with a helmet, of a smoke-excluding jacket attached thereto, and a receptacle attached to the jacket on the inside.

4. The combination with a helmet, of a smoke-excluding jacket attached thereto at its upper extremity, a belt connected with its lower extremity, and yielding means applied to the jacket in the zone of the belt, substantially as described.

5. The combination with a helmet, of a smoke-excluding garment attached to the helmet above, a belt attached to the garment below, and yielding means located in a pocket formed in the zone of the belt, substantially as described.

6. The combination with a helmet, of a

smoke-excluding jacket attached to the helmet, a belt attached to the lower part of the garment, and coil-springs located in a pocket formed in the zone of the belt.

5 7. The combination with a covering for the head, of a smoke-excluding garment attached thereto and adapted to be fastened to the body of the wearer below, and a number of receptacles attached to the front part of the garment on the inside and arranged one above another.

10 8. The combination with a covering for the head, of a smoke-excluding garment attached thereto and adapted to be fastened to the body 15 of the wearer below, a number of receptacles attached to the front part of the garment on the inside and arranged one above another, each receptacle having a brace adapted to bear against the body of the wearer, there being 20 an opening through the brace to permit circulation within the garment.

9. A smoke and gas excluding apparatus adapted to cover the head and body of the wearer and provided with an interiorly-located open receptacle, substantially as described.

10 10. A smoke and gas excluding apparatus adapted to cover the head and body as described, in combination with an exteriorly-30 located receptacle communicating with the space inclosed by the apparatus, the apparatus being also provided with an interior open receptacle for the purpose set forth.

11. A smoke and gas excluding apparatus adapted to cover the head and a portion of the 35 body of the wearer as described, in combination with a receptacle attached to the back of the apparatus exteriorly and provided with a conduit leading to the space inclosed by the jacket or garment, the apparatus being also 40 provided with an interiorly-located open receptacle.

12. A helmet and smoke-excluder comprising a covering for the head, and a jacket to be tightly fastened around the body of the wearer, 45 the device having a window in front, a closed interior receptacle attached to the jacket on the outside, and in communication with the space within the jacket, the device being also provided with an interiorly-located open receptacle for the purpose set forth.

13. The combination with a helmet, of a smoke-excluding jacket attached to the helmet, a belt attached to the jacket, interior and exterior receptacles attached to the jacket 55 which is provided with a transparent portion to enable the user to view surrounding objects, and an illuminating device mounted on the jacket, substantially as described.

In testimony whereof I affix my signature in 60 presence of two witnesses.

CROZIER T. THOMPSON.
